Primary Examiner — Elizabeth J Oswecki(74) *Attorney, Agent, or Firm* — Simmons Perrine Moyer Bergman PLC(57) **CLAIM**

The ornamental design for a beveled front security box, as shown and described.

DESCRIPTION

FIG. 1 is an isometric view of a beveled front security box showing our new design;

FIG. 2 is a bottom plan view thereof;

FIG. 3 is a front view thereof;

FIG. 4 is a back view thereof;

FIG. 5 is a left side view thereof;

FIG. 6 is a right side view thereof; and,

FIG. 7 is a top plan view thereof.

The matter shown in dotted lines is not a part of the invention.
